WEATHER STRIP

Filed July 27, 1931

UNITED STATES PATENT OFFICE

JAMES EVERETT BASHAM, OF DENVER, COLORADO, ASSIGNOR OF ONE-HALF TO
EPHRAIM G. MATSON, OF DENVER, COLORADO

WEATHERSTRIP

Application filed July 27, 1931. Serial No. 553,263.

This invention relates to a weather strip for windows and the like and has for its principal object the provision of a weather strip which can be quickly and economically installed; which will insure an absolutely weather tight joint between the window sash and the frame; and which will exert a constant pressure against the sash to prevent looseness and rattling.

Another object of the invention is to so construct the strip that it will not interfere with the removal of the sash when desired.

A further object of the invention is to so construct the strip that it will automatically accommodate itself to shrinkage and wear between the sash and the frame so as to always insure a tight joint.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

In the drawing:

Fig. 1 is a fragmentary perspective view through a typical sliding sash check rail window.

Fig. 2 is a detail perspective view illustrating the type or weather strip which is employed at the side of the frame, in the fully extended position.

Fig. 3 illustrates the same strip in the compressed position.

Fig. 4 is a detail cross section through the side of the frame taken on the line 4—4, Fig. 1.

Fig. 5 is a detail section illustrating the type of strip employed at the top and bottom of the frame.

In the drawing, the window sash is designated at 10, the side frame member is indicated at 11, the head frame member at 12, and the sill at 13.

Two types of strip are employed for the complete installation in a sliding sash frame. The first type, such as illustrated in Figs. 2, 3,

and 4, is employed at the side or sliding portions of the frame. The second type illustrated in Fig. 5, is employed at the top and bottom of the frame.

The first type comprises a channel member 14 open along one edge. The open edge is provided with two inwardly turned lips 15. A tongue member 16 projects between the lips 15 and is prevented from being withdrawn by side flanges 17. The tongue member 16 is formed of a single strip of sheet metal bent with a U-shape cross section and provided with outwardly turned edges forming the flanges 17. A plurality of bent leaf-springs 18 are distributed throughout the length of the channel member 14. These springs act to constantly urge the tongue 16 outwardly toward the position of Fig. 2.

The second style of strip comprises a length of sheet metal 19 bent along its medial line to form a tongue which spreads to form two parallel edges 20 which snugly engage each side of a wooden strip 21.

In installing the weather strip a groove is rabbeted in the side frame member 11 in the track of each sash 10. Another groove is rabbeted in the head frame member 12 over the top of the upper sash and still another groove is rabbeted in the sill 13 below the bottom sash 10.

A relatively narrow groove is now formed in the sides of both the sash and in the top of the upper sash and the bottom of the lower sash. Sections of the strip of Fig. 5 are now set in the grooves in the head member 12 and the sill 13 so that they will extend entirely across the opening. The channel members 14 are now cut to the height of the window and are set in the grooves in the side frame member 11. The outer extremities of the tongues 19 at the top and bottom of the window will pass through the open sides of the channel members 14 and rest against the top and bottom extremities of the tongues 16, forming a light joint at the corners.

The tongues 16 are now depressed to the position of Fig. 3 and the sash is swung into position. When the tongues 16 are released they will be forced outwardly by the springs 18 into the grooves 22 in the sash. The

grooves 22 are formed of less depth than the depth of the tongues 16 so that sufficient play will be allowed the springs 18 to constantly maintain the tongues 16 firmly against the bottoms of the grooves 22.

This spring pressure holds the sash snugly and prevents rattling. It also accommodates any shrinkage in the sash or wear in the grooves. Should it be desired to remove the sash this can be easily done by simply depressing the tongues 16 to the position of Fig. 3.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:—

1. A weather strip comprising: a channel member having a longitudinal opening along one of its edges; inwardly projecting lips 25 along the sides of said opening; a tongue member adapted to project outwardly from said channel member between said lips; projections formed on said tongue member to prevent withdrawal of the latter; and spring 30 means within said channel member arranged to constantly urge said tongue member outwardly.

2. A weather strip comprising: a channel member; inwardly turned edges on said channel member defining a longitudinal slot therein; a tongue member, said tongue member comprising a metal strip having a U-shaped cross section adapted to project through said slot; flanges formed on said tongue member to limit the projection thereof through said slot; and means for urging said tongue member outwardly.

3. A weather strip adapted to be positioned between a window frame and a window sash comprising: a channel member for placement in a groove in said frame; a longitudinal tongue member projecting from said channel member and arranged for placement in a groove in said sash; and means for continuously causing said tongue member to project from said channel member.

In testimony whereof, I affix my signature.

JAMES EVERETT BASHAM.
